CLAIM

The ornamental design for a handle for endoscope, as shown and described.

DESCRIPTION

FIG. 1 is a perspective view of a handle for endoscope showing our new design;

FIG. 2 is a left side elevational view thereof, the right side being a mirror image;

FIG. 3 is a front end elevational view thereof;

FIG. 4 is a rear end elevational view hereof;

FIG. 5 is a top plan view thereof;

FIG. 6 is a bottom plan view thereof;

FIG. 7 is a left side view thereof, showing the article in a status of use.

FIG. 8 is another left side view thereof, showing the article in a status of use; and,

FIG. 9 is a right side view thereof, showing the article in a status of use.

The broken lines depicting a hand in FIGS. 7-9 are for the purpose of illustrating environmental subject matter and form no part of the claimed design. The remaining broken lines depict portions of the handle for endoscope and form no part of the claim.

1 Claim, 9 Drawing Sheets
